RHEOSTAT SWITCH

William B. Dull, Coldwater, Mich., assignor to Kingston Products Corporation, Bronson, Mich., a corporation

Application June 9, 1954, Serial No. 435,403

3 Claims. (Cl. 201—48)

This invention relates generally to electrical switches and more particularly relates to a switch construction wherein a rotatably actuatable switch means is provided with an actuator member consisting of rigid synthetic resin having thermal and electrical insulative properties and being formed to provide a rotatable shaft having an integral radially extending enlarged portion confined within an enclosure and carrying and supporting the rotatable actuating parts of the switch.

The principles of the present invention find a particularly useful application when embodied in a rheostat switch construction, by way of illustrative example, a rheostat switch construction which may be adapted for automotive use and which may be carried on the dashboard of an automotive vehicle so as to be finger manipulable by the automobile operator or an automobile passenger.

With the switch apparatus and particularly with a rheostat switch, thermal energy is generated with the result that thermally conductive portions of the switch assembly become heated to an elevated temperature.

For example, in one form of rheostat switch apparatus utilized for controlling the blower motors of an automotive air conditioner installation, so much heat was generated that the finger manipulable portions of the switch assembly were uncomfortable to touch, thereby interfering with the proper operation of the switch assembly.

In attempting to overcome such problem, efforts were made to ventilate the switch, thereby maximizing the dissipation of thermal energy likely to be conducted by the thermally conductive portions of the switch apparatus.

Efforts were also made to reduce the number of components of the switch assembly and with particular regard to the possibility of reducing the number of thermally conductive components of the switch assembly.

Under some circumstances, however, it is highly desirable that the actual finger manipulable actuating member of the switch be made of a metal material decoratively enhanced by chrome or nickel plating, a form of material having good thermal conductivity characteristics and having the effect, therefore, of offsetting the objectives of the enumerated proposals for the provision of an improved switch structure.

In accordance with the principles of the present invention, there is provided an improved switch assembly which not only utilizes a reduced number of highly simplified components but also a switch assembly which utilizes an actuating member consisting of a rigid synthetic resin having thermal and electrical insulative properties and which affords a design flexibility permitting the use of chrome or nickel plated actuating knobs.

These objectives are attained in accordance with the principles of the present invention by providing a switch construction utilizing a sheet form member bent to provide a centrally apertured radially extending wall having circumferentially spaced longitudinal tongues. A base assembly is carried by the tongues in spaced relation to

2

the wall, thereby to form an enclosure. Rotatably actuatable switch means are provided in the housing and may take the form of an arcuately shaped helically wound coil forming a rheostat resistance. An angularly adjustable rotatable actuator member is provided within the enclosure and engages the coil as well as a contact terminal carried by the base assembly.

To adjust the actuating member and to carry the actuating member rotatably within the enclosure, there is provided a rigid synthetic resin shaft, the shaft being made of a material having favorable thermal and electrical insulative properties such as molded nylon or the like. At one end of the shaft inside of the enclosure there is provided an enlarged radially extending portion for carrying the actuating member. The shaft projects through and is rotatably journaled in the centrally apertured radially extending wall so that the opposite end of the shaft extends into a manually accessible location spaced away from the enclosure. A suitable actuating knob may be fastened to the free end of the shaft, which knob may be conveniently made from a metal decoratively enhanced by chrome or nickel plating, however, the knob will be electrically and thermally insulated by virtue of the nylon shaft. Furthermore, the radially extending wall may be provided with means having a metallic bearing surface so that the nylon shaft will be journaled and virtually self-lubricated, it being appreciated that nylon engaging with metal exhibits favorable anti-friction characteristics.

It is an object of the present invention, therefore, to provide an improved switch construction utilizing a reduced number of simplified parts which are convenient and economical to fabricate and which are completely reliable and rugged in use.

Another object of the present invention is to provide a switch construction having a shaft actuator consisting of a rigid synthetic resin having thermal and electrical insulative properties.

A further object of the present invention is to provide a rheostat switch which is manually actuatable and wherein the finger manipulatable portions thereof will not be heated to an elevated temperature even if made from material having high thermal conductivity.

A still further object of the present invention is to provide a switch construction wherein a movable contact carrier and a rotatable actuating shaft therefor are integrally made as a one piece molded synthetic resin material.

Yet another object of the present invention is to provide a switch construction wherein a rotatable switch actuator consists of an integral one piece member providing a longitudinally extending rotatable shaft for receiving a manually engageable actuating knob.

Many other features, advantages and additional objects of the present invention will become manifest to those versed in the art upon making reference to the detailed description which follows and the accompanying sheet of drawings in which a preferred embodiment of a switch construction embodying the principles of the present invention is shown by way of illustrative example.

On the drawings:
Figure 1 is an exploded view of a switch construction showing parts in elevation and showing other parts broken away and in cross-section showing the components provided in accordance with the principles of the present invention.

Figure 2 is an elevational view of an assembled switch, omitting the actuating knob.

Figure 3 is an end elevational view of the assembled switch shown in Figure 2.

Figure 4 is an end elevational view of the actuating

member provided in accordance with the principles of the present invention.

Figure 5 is an end elevational view showing the other end of the actuator member of Figure 4, and

Figure 6 is a partial or fragmentary cross-sectional view showing additional details of construction of the actuator member and illustrating the positioning of the biasing spring thereon.

As shown on the drawings:

The switch construction of the present invention is illustrated generally at 10 and comprises a sheet form housing member 11 bent to provide a radially extending wall 12 which is centrally apertured as at 13 and which has a longitudinally extending rigidifying peripheral flange 14. The housing member 11 is further characterized by the provision of a plurality of circumferentially spaced longitudinally extending tongues 16. In the present embodiment, there are three tongues 16, each decreasing in size towards one end thereof so as to terminate in a lip portion indicated by the reference numeral 17.

A generally cylindrical and tubular stem member 18 is provided. The stem member 18 has a longitudinally extending bore 19 which provides a metallic bearing surface in register with the central aperture 13 of the radial wall 12. One end of the stem member 18 is received within the central aperture 13 and staked portions indicated at 19 retain the stem member 18 in firm assembly with the housing member 11. The stem member 18 is peripherally threaded as at 20 to facilitate mounting of the switch assembly 10 on the dashboard of an automobile or upon some other mounting surface.

A base assembly indicated generally at 21 comprises a disc shaped ceramic body having a plurality of circumferentially spaced through holes 22 extending longitudinally therethrough. The ceramic body has opposed faces 23 and 24. Secured to the face 23 is an annular stationary contact plate 26. The plate 26 is retained by a rivet 27 extending longitudinally through the ceramic body and also serving to retain a contact terminal 28 which extends longitudinally from the face 24 of the ceramic body.

The face 23 of the ceramic body is further characterized by the provision of an arcuate groove 29 which lies in longitudinal register with the through holes 22 and which receives an arcuately shaped helically wound resistance coil 30 cemented or otherwise firmly connected to the ceramic body. A contact terminal 31 is electrically connected to the coil 30.

On the face 24, there is provided a plurality of circumferentially spaced recesses 32 which receive the bent over lips 17 of the tongues 16 thereby placing the base in assembly with the housing member 11, the ceramic body lying in longitudinally spaced relation relative to the radially extending wall 12. Furthermore, the base assembly 21 together with the housing member 11 forms an enclosure 33 in which the switch actuating means are confined.

First of all, there is provided a rotatable actuating member which takes the form of a contact plate indicated at 34. The contact plate 34 is made of electrically conductive material and has terminal portions 36 which slidably engage the contact plate 26.

A second contact terminal portion 37 is provided by a peripheral embossment formed on the plate 34 in register with a longitudinally extending contact face provided by the coil 30, which face projects longitudinally beyond the radial face of the ceramic body.

In accordance with the principles of the present invention, an actuator member indicated generally at 40 is provided, which member 40 consists of a rigid synthetic resin having thermal and electrical insulative properties and being formed to provide a rotatable shaft 41 which is journaled in the bearing surface 19 and which projects

through the central aperture 13 and the stem member 18 to the outside of the enclosure 33.

At one end of the actuator member 40 there is provided a radially extending enlarged portion 42. The enlarged portion 42 is longitudinally grooved as at 43 on opposed sides thereof to slidably receive and guide a pair of longitudinally offset lugs 44 provided on opposite sides of the contact plate 34.

As shown in Figure 4, the enlarged portion 42 also has an upstanding circular boss 46 formed on the end face thereof and spaced concentrically inwardly of arcuately shaped shoulders 47 and 48 respectively, thereby to provide a generally annular recess 49 receiving and seating the end of a coil spring 50 inserted as a continuous biasing means between the contact plate 34 and the actuating member 40.

It will be appreciated that the peripheral surface of the shaft portion 41 of the actuator member 40 is approximately the same diameter as the bearing surface provided by the bore 19 extending longitudinally through the stem member 18. It will be further appreciated, therefore, that the enlarged radially extending portion 42 on the end of the actuator member 40 is considerably larger in size than the bore 19, thereby to effect a confinement thereof within the enclosure 33 when the housing member 11 is assembled to the base assembly 21. The continuous biasing means in the form of the coil spring 50, therefore, has the effect of loading the actuator member 40 in one direction and in loading the contact plate 34 in an opposite direction into spring bias contact with the contact plate 26 and the resistance coil 30.

At the other end of the actuating member 40, there is provided a flat 51 adapted to seat a set screw 52 carried by a manually engageable actuating knob.

Since the actuating member 40 is made of a rigid synthetic resin having thermal and electrically insulative properties, it will be appreciated that the knob 53 may be made of a metallic material capable of being decoratively enhanced by a chrome or nickel plating, yet such knob 53 will be insulated from the switch mechanism both thermally and electrically.

The terms "insulator" and "conductor" with respect to both heat and electricity are well understood by those skilled in the art, notwithstanding the fact that all materials are generally considered to have at least limited heat and electrical conductivity and no material is considered to be a perfect insulator. For the purpose of simplification in this specification, it will be noted that heat conductors are generally considered to have a thermal conductivity constant "k" which is defined as the quantity of heat (B.t.u. or calories) that flows in a unit of time (one hour or one second) through a unit area of plate (one sq. ft. or one sq. cm.) of unit thickness (one ft. or one cm.) having unit difference of temperature (1° F. or 1° C.) between its faces. The thermal conductivity of different materials varies greatly. For metals and alloys "k" is high, while for certain insulating materials such as asbestos, cork and kapok, "k" is very low. Herein heat conductors will be considered to have a thermal conductivity constant "k" of as much as about 10 (in the case of highly resistant alloys used as heating elements) and preferably of as much as about 30; whereas the ordinary insulating materials have heat conductivity constants "k" of less than 1 and usually less than 0.1.

In the electrical arts, electrical conductors are usually understood to have resistivity which is defined as the resistance of a sample of the material having both a length and cross-section of unity. The resistance of a centimeter-cube and circular-mil-foot are the two most common units of resistivity. Herein electrical conductors are understood to have resistivities, in micromhos per cm.³, of not more than about 100 (as in the case of the "Nichrome" heating elements) and preferably not more than about 75 20; whereas the resistivity of the insulators is usually

considered to be at least about 10^5 ohms per cm^3 , and preferably 10^{10} ohms per cm^3 .

One synthetic resin which has been used successfully in accordance with the principles of the present invention is molded nylon. The thermal conductivity of the nylon material utilized in the construction of the actuating member 40 has a thermal conductivity of 5.2-5.8 (measured in terms of 10^{-4} calories per second per square centimeter per 1°C . per centimeter). The volume resistivity of the nylon material utilized is in the range of 4.5×10^{12} - 4×10^{14} (measured in terms of ohm- cm^3 with 50% relative humidity and 23°C .)

Although various minor structural modifications might be suggested by those versed in the art, it should be understood that I wish to embrace within the scope of the patent warranted hereon all such modifications as reasonably and properly come within the scope of my contribution to the art.

I claim as my invention:

1. A rheostat switch assembly comprising, a ceramic base plate having a plurality of circumferentially spaced longitudinally extending through holes formed therein, an arcuate groove formed in one face of said plate in register with said through holes, an arcuate complementary shaped resistance coil received in said groove and supported by said base plate, a contact terminal plate carried by said base plate, said resistance coil being ventilated by air flowing through said base plate at said through holes, a rotatable bridging plate having terminal portions engaging said coil and said contact plate and actuating means for adjustably rotating said bridging plate relative to said base plate, said actuating means consisting of a one-piece member made of electrically and thermally non-conductive material and providing an enlarged bridging plate carrying portion and a shaft portion integral therewith and extending longitudinally away therefrom, said ceramic base having a housing connected thereto providing a bearing portion for journaling said shaft and confining said enlarged bridging plate carrying portion, a continuous biasing spring between said bridging plate carrying portion and said bridging plate loading said bridging plate against said resistance coil and said contact plate, circuit means to be controlled by said rheostat switch assembly including contact terminal means connected to said resistance coil and said contact plate, and a manual actuating knob carried on the free end of said shaft portion.

2. A rheostat switch construction comprising a sheet-form housing member bent to provide a longitudinally flanged radially extending centrally apertured wall having a plurality of longitudinally extending circumferentially spaced tongues on the outer periphery thereof, a base assembly longitudinally spaced from said radially extending wall and having a plurality of recesses corresponding in number and circumferential spacing to said tongues, the end of said tongues being bent over and received in said recesses to connect said base assembly to said housing

member, thereby to form a housing enclosure, a generally tubular stem member having one end received in and connected to said centrally apertured radially extending wall and providing a longitudinally extending bore forming a metallic bearing surface, the outer periphery of said stem member being threaded, contact terminal means on said base assembly including a resistance coil, said base assembly having a row of ventilating apertures extending therethrough in register with said resistance coil, a rotatable switch actuator member inside of said housing enclosure bridging said contact terminal means and said resistance coil, and a one-piece plastic shaft having low thermal conductivity and being electrically insulative, said shaft having an enlarged carrier portion forming one end thereof confined in said housing enclosure to mount said switch actuator member and to retain said shaft in assembly within said housing enclosure, said shaft further including a reduced shaft actuating portion projecting out of said housing enclosure through said centrally apertured wall through said stem member, said actuating portion having a peripheral surface journaled for rotation by said metallic bearing surface, said shaft having means formed at the actuating portion end thereof to receive a manually manipulable actuating knob electrically and thermally insulated from the contact terminal means.

3. A rheostat switch construction comprising a housing having a generally cylindrical neck providing a metallic bearing surface, a shaft member made of plastic material and having a reduced diameter rod-like actuating portion extending axially outwardly through said neck, said actuating portion having a peripheral journaling surface journaled for rotation by said bearing surface, an integral enlarged carrier portion forming one end of said shaft member and being confined inside of said housing to retain said shaft member and assembly with said housing, switch means in said housing including a rotatable switch actuator member carried on said enlarged carrier portion of said shaft member, the actuating portion of said shaft extending axially outwardly of said neck into a manually engageable position for actuation of said switch construction and being electrically and thermally insulated from said switch means by said plastic material, said switch means further including an apertured ceramic base plate having a resistance coil carried thereby in register with said apertures for ventilation thereof and engaged by said actuator member.
